(57) CLAIM

The ornamental design for a body portion of a canine poncho, as shown and described.

DESCRIPTION

FIG. 1 is a top view of a body portion of a canine poncho; FIG. 2 is a right side view, where the left side is a mirror image of the right side; and, FIG. 3 is a bottom view thereof.

The broken lines are for the purpose of illustrating unclaimed portions of the body portion of a canine poncho and form no part of the claimed design.
